CLAIM

The ornamental design for a wet wipe warmer, as shown and described.

DESCRIPTION

FIG. 1 is a first perspective view of a wet wipe warmer showing my new design;

FIG. 2 is a second perspective view thereof;

FIG. 3 is a front elevational view thereof;

FIG. 4 is a rear elevational view thereof;

FIG. 5 is a left elevational view thereof;

FIG. 6 is a right elevational view thereof;

FIG. 7 is a top plan view thereof;

FIG. 8 is a bottom plan view thereof;

FIG. 9 is an enlarged view of a portion labelled by a numeral 9 of FIG. 1; and,

FIG. 10 is a perspective view of the wet wipe warmer in a state of use when the cover is open.

The broken lines and adjacent unshaded areas in the drawings illustrate portions of the wet wipe warmer which form no part of the claimed design.
